UNITED STATES PATENT OFFICE.

DANIEL B. MEDANICH, OF BUECHEL, KENTUCKY.

OILING SYSTEM FOR INTERNAL-COMBUSTION MOTORS.

1,299,757.

Specification of Letters Patent. Patented Apr. 8, 1919.

Application filed September 6, 1917. Serial No. 189,953.

To all whom it may concern:

Be it known that I, DANIEL B. MEDANICH, a citizen of the United States, residing at Buechel, in the county of Jefferson and State of Kentucky, have invented a certain new and useful Improvement in Oiling Systems for Internal-Combustion Motors.

This invention relates to an oiling system for internal combustion motors, and an object is to provide means whereby oil from a central source of supply will be positively and continuously delivered to the valves, cylinders and bearings of such a motor.

To the accomplishment of the foregoing and related objects, said invention consists of the means hereinafter fully described, and particularly pointed out in the claims.

The annexed drawing and following description sets forth in detail certain mechanism embodying the invention, such disclosed means constituting however but one form in which the principle of the invention may be used.

In the drawing, wherein similar reference characters designate like parts in the several views, Figure 1, is a transverse sectional view of a motor embodying my invention: Fig. 2, a plan view of same.

As shown in the drawing, —10— designates a power cylinder which is mounted upon a crank case —11—, of approved construction, within which are mounted respectively, a piston —12— and a crank shaft —13—, the latter being connected with the former by means of a connecting rod —14—, whereby motion is transmitted from the piston to the crank shaft. The motor illustrated is of the pattern popularly known as T head, exhaust and intake valve cylinders —15, 16— being disposed respectively on opposite sides of the power cylinder and communicating therewith by means of ports —17, 18—. A water jacket —19— envelops the power and valve cylinders. The valve cylinders are open at their lower ends to the atmosphere. In the upper end of each valve cylinder is an internal annular valve seat —20— in a line with, or just above the upper end of the power cylinder, against which, piston valves —21, 22— close. Valve rods —23— are connected with the cylinders by suitable means such as ball joints —24— and depend therefrom into position to be ac-

tuated, to open the valves, through the medium of levers —25—, by means of cams 55 —26—. The cams are secured on shafts —27— which receive motion from the crank shaft by suitable means such as belts —28—. Springs —29— serve to return the valves to 60 the closed position. The inlet valve cylinder communicates at its upper end with a transverse passage —35— which extends across the head of the motor, and at its outer end is provided with means such as a flange 65 —36— for the attachment thereto of a conduit which leads to a suitable source of fuel supply. The passage 35 divides and passes around a well —37— within which is located a spark plug —38—. An exhaust tube 70 —39— leads from the upper end of the exhaust valve cylinder through the intake passage 35, the arrangement being such that incoming fuel impinges upon said tube and is heated by contact therewith. An internal 75 annular groove —40— provided in each valve cylinder is supplied with lubricating oil from a suitably positioned container —41—, by means of conduits —42, 43—. Passages —44— lead from the grooves 40 in 80 the valve cylinders to an internal annular groove —45— in the power cylinder. A tubular pin —46— which extends diametrically through the piston, is the medium 85 whereby the connecting rod is joined therewith, and at each reciprocation of the piston as the open ends of the pin passes the groove 45, oil enters the pin and through an opening —48— in the side thereof issues into a passage —49— which extends along the connecting rod and conducts the oil to the connecting rod bearing —50—, illustrated here-with as being a ball bearing. The rapid movement of the balls, in the bearing, past the orifice of passage 49, creates a suction 90 therein which causes a continuous flow of oil therefrom. It is to be understood that the size of various conduits, grooves and passages is so designed as to furnish a proper quantity of oil to the pistons, which present 100 broad bearing surfaces, with the result that more oil reaches the bearing 50 than it requires, and the surplus is thrown out in every direction, by centrifugal force, against the inner surface of the crank case, down 105 which it flows and accumulates in the bottom thereof. A portion of the oil thrown off

the bearing, passes through openings 51 in the crank case into the compartments in which are the cams, and serves to keep them properly lubricated. A portion of the oil, as it trickles down the walls, will be caught in a trough, or gutter, 52, which is arranged along the inner side of the crank case at a suitable distance above the level of the crank shaft. From the trough 52, the oil flows, by a conduit—53—to a point whence it will drop therefrom on the crank shaft bearing—54.

It will be observed that by the arrangement described, a continuous flow of oil is assured to all the principal bearing surfaces, from one source of supply.

It is thought that the many advantages of my improved oiling system, will be apparent to those skilled in the art pertaining thereto, and it will further be evident that changes, variations and modifications may be resorted to without departing from the spirit of the invention or sacrificing any of its advantages, and I therefore do not wish to restrict myself to the details of construction hereinbefore described, and as shown in the accompanying drawing, but reserve the right to make such changes, variations and modifications as come properly within the scope of the protection prayed.

Having thus described my invention so

that those skilled in the art pertaining thereto may make and use the same, I claim:

1. In a motor as characterized, a valve cylinder having an internal annular groove, means for supplying oil thereto, a power cylinder having an internal annular groove, means for leading oil thereto from the first named groove, a piston reciprocably mounted in the power cylinder, a tubular pin having a lateral opening extending transversely through the piston, a connecting rod provided with a longitudinal oil passage movably positioned on said pin so that said passage registers with the lateral opening therein.

2. In a motor as characterized, a power cylinder having an internal annular groove, exhaust and intake valve cylinders disposed respectively on each side of said power cylinder, each of said valve cylinders having an internal annular groove, an oil container, means for delivering oil from said container to the grooves in the valve cylinders, means for leading oil from the grooves in the valve cylinder to that in the power cylinder, a tubular piston pin having a lateral opening, a connecting rod having a longitudinal oil passage, the entrance to which registers with said opening.

DANIEL B. MEDANICH.
